Fig. 1

FIG. 1 is a top view of a golf club head cover showing my new design;

FIG. 2 is a back view of the golf club head cover;

FIG. 3 is a side view of the golf club head cover; and

FIG. 4 is a front view of the golf club head cover.

The characteristic feature of my design resides in the pinched-in effect at the top of the head cover.

I claim:

The ornamental design for a golf club head cover, as shown and described.
